UNITED STATES PATENT OFFICE

2,455,461

INDIVIDUAL CONTAINER SEALER

Edward E. Anderson, Loma Linda, Calif.

Application March 30, 1945, Serial No. 585,637

1 Claim. (Cl. 226—86)

1

This invention pertains to a simple, inexpensive device for applying a cover made of a sheet of flexible material such as Cellophane, to the top of a carton, tube, container or the like.

Many foodstuffs and other commodities are being dispensed in cartons or containers made of paper which is either impregnated or coated with wax, paraffin or other heat-responsive material adapted to increase the strength and render the body of the container impermeable to moisture. Cottage cheese and many other articles are dispensed in such packages. In many instances these containers are of the open top variety and it is only necessary to apply a sheet of material such as Cellophane, over the open top in order to protect the contents from contamination. Often the grocer or retail distributor fills such containers from bulk supplies and the housewife uses the container only as a means of carrying the product from the store to her home. Strong or permanent coverings or seals are not essential under such conditions.

The present invention, therefore, is directed to a small, simple, yet efficient device whereby the individual grocer or storekeeper may rapidly and easily cover and seal small containers.

Generally stated, the invention relates to a device whereby the clerk or other operator may place a sheet of Cellophane or other heat-responsive material over the open top of a container which he has filled with the desired product and by the actuation of a single element, cause such cover sheet to conform to the upper edge areas of the container and be heat-sealed thereto. In the device of the present invention means are provided whereby the single energizing member lifts the container into sealing position and also actuates the heat-sealing elements, the movements of the heat-sealing elements and of the lifter being so correlated that the container is maintained in lifted position while the heating elements move toward and away from the closure. In one of the forms of devices embraced by the present invention, means are provided whereby a yielding pressure is maintained upon the container and adjustments may be readily made so that containers of different sizes may be handled.

It is an object of the present invention, therefore, to disclose and provide a simple and efficient device for sealing the covers of fibrous containers.

Another object of the invention is to provide a device which may be operated either manually, electrically or by pressure fluid, in which a sin-

2

gle reciprocatable energizing member actuates the elements in timed relation.

These and other objects of the invention will become apparent to those skilled in the art from the following description. In order to facilitate understanding, reference will be had to the appended drawings, in which:

Fig. 2 is a front elevation of one form of machine.

Fig. 2 is a side elevation.

Fig. 3 is a plan view.

Fig. 4 is a side elevation partly in section of a modified form of machine.

As previously stated, the machines of this invention are particularly adapted for use by grocers and other shopkeepers. It is recognized that various capping and sealing machines have been devised heretofore but substantially all of these prior machines are for use in factories or plants which produce tremendous numbers of containers filled with condiments, foodstuffs, etc. Such large complicated machines are not adapted for use by an individual grocer.

The machine shown in Figs. 1, 2 and 3 is a manually operable machine and consists of a vertical framework 10 supported by the base 11, the framework being provided with a work table 12 at a suitable height. A standard 13 extends above the work table 12 and carries an annulus 14, the internal opening being indicated at 15. The standard 13 also carries a circular plate 16 having downwardly extending lips at its outer edges so as to form a downwardly extending cup or recess 17. The annulus 14 and the plate 16 are in parallel, vertically spaced, stationary relationship.

A pair of opposing semi-circular heating elements 18 and 19 (best shown in Fig. 3) are pivotally mounted upon the standard 13 so as to be movable toward and away from each other in a zone between said annulus and plate. The elements 18 and 19 may have preformed heating elements carried by their inner concave surfaces as indicated at 18' and 19'. The heating elements per se may be supplied with electric current from any suitable source and in order to maintain such elements at a desired temperature, a thermostat 20 may be carried by one or both of the elements. In order to simplify description, the jaws or carriers together with their heating elements will be generically referred to as heating elements.

A circular recess formed in the work table 12 immediately beneath and in axial alignment with the annulus 14 contains a lifting plate 21 mounted

upon the upper end of a rod 22 extending through a suitable sleeve or bearing 23 carried by the lower side of the work table 12. The lower end of the rod 22 rests upon a lever 24 pivoted to the frame or standard 10 at 25. A cup 26 may be carried by the lever 24, the end of the rod 22 fitting loosely into the cup.

A foot treadle 27 pivoted to the frame at 28 is provided with a bifurcated end portion 29 extending around an upstanding reciprocatable energizing member 30 carrying a stop or cross piece 31 which normally rests upon the bifurcated end 29 of the treadle 27. The upstanding reciprocatable member 30 is provided with an adjustable collar 32 fastened thereon against which a compression spring 33 rests, the upper end of the spring bearing against a folding collar which supports the lever 24. The upper end of the energizing member 30 slidably fits into a sleeve or cylinder closed at the upper end, the upper end of the sleeve having toggle links 35 and 36 pivotally attached thereto as at 37, the other ends of the links being connected to levers 38 and 39 respectively. The levers 38 and 39 are pivoted as at 40 and 41 to a cross member 42 of the supporting frame. The upper ends of such levers 38 and 39 are preferably provided with ball ends fitting into sockets formed in the jaw elements 19 and 18. Springs 44 and 45 are connected to the lower portions of levers 38 and 39 for the purpose of facilitating return of the jaw elements 18 and 19 to their normal open position. A compressible spring is contained within the sleeve fitting over the end of member 30 for the purpose of delaying the movement of the toggle and levers until the lifting plate has been actuated.

In operation, the operator, having filled a suitable container with the desired product, places a sheet of Cellophane or other heat-responsive material over the top of the container and then places the assembly upon the lifting plate 21. By actuating the treadle 27, upward movement is imparted to the energizing member 30. Such upward movement actuates the lever 24 and causes the lifting plate 21 to rise, thereby moving the upper portion of the container through the annulus 14. The annulus permanently folds the sheet of material around the edge of the container. The top of the container then enters the circular plate 16 and the lip of such plate folds the sheet material around the edge. The sheet material is pressed into contact with the upper edge of the container. A yielding pressure is maintained by the lifting plate against the bottom of the container as the energizing member 30 continues its upward travel, the additional upward travel being absorbed by the spring 33. Such additional upward travel, however, actuates the toggle links 35 and 36, causing the levers 38 and 39 to pivotally move the heating elements 18 and 19 toward each other so as to encircle and firmly press against the sides of the container in a zone immediately beneath the upper edge of the container. The heating elements thus firmly press and simultaneously heat the Cellophane or other covering sheet against the container and cause such covering sheet to be heat-bonded to the container.

When pressure is removed from the treadle 27, the springs 44 and 45 return the jaws or heating elements 18 and 19 to their original open position and the lifting plate 21 is not lowered until the energizing member 30 has moved a considerable distance so that the spring 33 is substantially

fully expanded. In this manner the container is not withdrawn from the device until the jaws 18 and 19 have opened, thereby permitting a container having a bead or outward flange at its upper end to be maintained within the device until the jaws have opened.

The device illustrated in Fig. 4 is a table model capable of being used upon a counter, shelf or the like. It consists of a suitable lower housing 50, the upper surface of which furnishes a work table 12. The standard 13 extends upwardly and supports the annulus 14 and the upper circular plate 16 as described hereinbefore. The semi-circular heating elements 18 and 19 are here provided with rearwardly extending integral fingers 58 and 59, the rearward ends of such fingers being provided with downwardly extending lips. Toggle links 60 are connected to the downwardly extending lips of the fingers 58 and 59 and to a bifurcated end portion 61 of a reciprocatable energizing member 62 which is connected to a piston 63 in a pressure cylinder 64 located within the housing 50. A lever 65 pivoted at 66 and provided with a forked end 67 engages a cross pin 68 extending through the energizing member 62. The opposite end of such lever 65 is pivotally connected to a plunger 69 as at 70. The plunger 69 extends into a hollow shaft 71 connected to a lifting plate 21 which is normally supported within a recess formed in the top or work table 12. A spring 73 is contained within the hollow shaft 71 and bears against the top of the plunger 69. A container to be sealed is indicated at 74 and the sheet of superimposed Cellophane or the like is indicated at 75.

The fluid pressure cylinder 64 is provided with conduits connected to the top and bottom thereof as indicated at 77 and 78, these conduits leading to a four-way valve 80. The valve is supplied with pressure fluid through line 81 from a pump 82 driven by a suitable electric motor. The pump is supplied with fluid from a reservoir 83 and the valve 80 is also provided with a return line 84 leading back to the reservoir. A suitable pressure relief valve may connect the pressure line 81 with the return line 84 as indicated at 85.

In the position illustrated in Fig. 4 the device is ready to seal the container. By imparting a quarter turn to the valve 80, the pressure line 81 may be connected with the line 78 leading to the top of the cylinder 64 while simultaneously the bottom of said cylinder is connected by line 77 to the return line 84. Downward movement of the energizing member 62 will cause lever 65 to raise the plunger 69 and the lifting plate 21 so as to cause the top of the container to pass through the annulus 14 and bear against the recess in the top plate 16. Continued downward movement of the member 62 will actuate the links 60, causing the semi-circular heating elements 18 and 19 to grasp and press the cellophane 75 against the container 74. By again turning valve 80 to its original position, the direction of flow of pressure fluid to the cylinder is reversed and the parts return to the position indicated in Fig. 4, thereby lowering the completely sealed container. A completely enclosed hydraulic system of this type has been found very satisfactory.

It is to be understood that instead of employing liquid pressure, pneumatic pressure may also be used. Electromagnetic means or solenoid means may also be employed.

75 It is to be understood that the invention is

not limited to the specific embodiments illustrated. Those skilled in the art will readily appreciate that various changes may be made. In actual practice it has been found that Cellophane may be rapidly and effectively caused to adhere to the waxed or coated exterior surfaces of food containers and adequately protect the contents against contamination.

I claim:

An individual container sealing machine comprising: a work table, a lifting plate in said work table, an annulus provided above the lifting plate, a circular plate provided with a downwardly extending lip at its outer edge positioned above the annulus and in alignment therewith; a pair of opposing semi-circular heating elements movable toward and away from each other in a zone between said annulus and plate to grasp and release a container whose top extends through the annulus; a vertically extending reciprocatable energizing member, means for moving said member, a toggle linkage between said member and

10

15

20

said heating elements for imparting simultaneous and opposing movement thereto, lever means for raising and lowering the lifting plate; and means connecting the energizing member with said lever for moving the lifting plate, said means including a spring whereby the lifting plate is maintained in yielding contact with a container while the energizing member continues to move.
